UNITED STATES PATENT OFFICE

2,692,445

ROTARY SNOWPLOW

Rex C. Darnell, Dexter, Mich.

Application June 24, 1948, Serial No. 34,873

1 Claim. (Cl. 37—43)

1

This invention relates to a rotary snow plow and has particularly to do with a system and apparatus for removing accumulated snow from roads, walks and other surfaces.

The present invention contemplates a power-driven snow plow of the type having a blower for dispelling snow fed thereto. It is an object to provide a snow plow which is self-propelling and which may be readily operated by one man.

Another object of the invention is the provision of a traction means for a plow which will not clog or slip in any condition of the snow or ice on which it is running.

A further object of the invention is the provision of a vacuum fan and feed arrangement in which snow is moved from a feed auger back to a fan vortex without any packing or concentration thereof and thus eliminating danger of fouling. In addition a backed fan is used to prevent ice and snow film from hindering the fan rotation.

For use in a tractor type plow of the hand-type it is essential that a light power system be utilized to its greatest efficiency since it must propel the tractor, drive the feed auger and drive the dispelling fan. The present invention contemplates a light, well balanced unit fully stabilized and adjustable for snow depth. It contemplates also a unit in which, regardless of snow depth, fouling and stalling are prevented with substantially constant speed auger and fan operation. Reverse of fan direction is permitted together with reversal of snow throw, and vacuum regulation insures maximum efficiency of auger and fan at all times.

Another object of the invention is the provision of a hand control system for immediate adjustment of forward speed and auger height without stopping the tractor movement.

An additional related object is the provision of an inexpensive traction speed control device adaptable to quick and easy adjustment.

Other objects and features of the invention relating to details of construction of the feed auger, general construction for winter operation, and details of operation will be more fully described in the following description and claims.

I am presenting drawings to illustrate the features of my invention and the various views may be briefly described as:

Figure 1, a side view of an assembled tractor showing the position of operation.

Figure 2, a front view of the snow remover showing the auger arrangement.

2

Figure 3, a vertical section view of the unit showing various details of construction.

Figure 3A, an elevation of a clutch control handle.

Figure 4, a plan view of the snow plow tractor showing some of the details of the power connections and controls.

Figure 5, a sectional view on line 5—5 of Figure 3 omitting the feed screw for clarity.

Figure 6, a sectional view of a transmission and speed control means showing certain parts displaced for clarity.

Figure 7, a detail view of a transmission drive for the fan and snow auger showing a reverse mechanism for the fan.

Figure 8, a diagrammatic sectional view on line 8—8 of Figure 4, limited to the speed drive control.

Figure 9, a sectional view of a portion of a traction wheel taken on line 9—9 of Figure 1.

Figure 10, an enlarged view of a slip joint used in speed control.

Figure 11, a vertical section through the axle showing only the frame, axle drive, and wheel.

Figure 12, a section of the ratchet wheel drive on line 12—12 of Figure 11.

Figure 13, a vertical lengthwise section of the frame.

Figure 14, a detail of the axle bearing support; and

Figure 15, a detailed view of a cover plate fastening means.

Referring first to Figures 1, 2 and 3, the traction means for the tractor consists of wheels 20 having traction rims 21. These wheels are suitably mounted on an axle 22 which supports a mounting frame through journal plates 22A on side walls 23 and 24 forming part of the frame of the tractor. These walls 23 and 24 rise from a common bottom plate and are connected by inverted U-shaped angle members 25 and 26 at each end of the housing (Figs. 11 and 13). The walls 23 and 24 are angled at the top edge and slotted at 27 to receive the axle 22. The top edges are reinforced by angle bars and the slot may be bridged by a reinforcing strap 27A. A cover plate, described later, completes the housing. An engine 28 is supported on the mounting frame at the rear of the tractor housing, and the oil sump 29 rests on the bottom plate 30 which is integral with the side plates 23 and 24. Pivoted to each side wall of the main frame section, as shown best in Figure 4, is a yoke 32. The

pivot points may be identified as 33 and 34. At the back central portion of the yoke 32 is a widened portion 36 provided with a vertical bore to receive the stanchion 38 of a caster wheel support 39. The caster wheel 40 is mounted in suitable bearings in the bifurcate support 39 and furnishes support for the rear portion of the assembly. The machine is so designed that the center of gravity lies behind the axle 22. The wheel 40 also absorbs any torque reaction developed in operation. 10

The yoke 32 has a flared end 43, Fig. 3, which extends forwardly of the pivot point 33. This end has rack teeth 45 which are positioned to cooperate with a bell crank latch 46 pivoted at 47. This latch is held in locked position by a spring 48 and is controllable by a rod 50 which extends rearwardly to a point adjacent the left grip 52 of handle shafts 54 which are fastened at 55 to the respective sides 23 and 24 of the main frame. The handle shafts 54 are connected by a bar 56. Pivoted on the left handle 54 is an actuating lever 57 projecting toward the grip 52 and connected to the rod 50 so that thumb or finger action on the lever 57 will permit locking latch 46 to be released. Thus the position of the caster wheel 40 may be shifted relative to the assembly. This shifting will raise or lower the front end of the machine.

At the front end of the machine, mounted on the frame made up of the bottom plate 30 and side walls 23 and 24 joined by U-shaped angle members 25 and 26, is a fan housing 60 and a feed or distribution housing box 62. On the fan housing 60 is a snow spout 64 with an outlet opening 65 directed up and to the side of the machine. This outlet housing 64 is fastened by swinging wing nuts at 66 so that it may be readily reversed to direct cleared snow to the left rather than to the right.

The contour of the fan housing 60 is best shown in Figures 3 and 5. The housing 60 is closed at the front by a wall 67 at the bottom and a wall 68 at the top, each of which are joined to the housing 62. The housing 62 has a relatively flat cover box 69 which forms the top of the housing and the sides 69A, and 69B down to the centerline of the fan.

The lower portion of housing 62 is formed by a shaped piece 70 which at the front edge forms horizontal and vertical leading edges of the snow scoop. The walls of this scoop are shaped and blended back to a circular opening 71 at the lower half of the fan and smaller than the fan radially. The sides 72 and 74 join with sides 69A and 69B of the top box cover 69 and are joined with the front wall 67 which completes the front of the fan housing around to the horizontal centerline of the fan. The plate 68 which forms the front of fan housing 60 also extends between housings 60 and 62 to complete the fan opening at 68A. At the front edge of the walls 72 and 74 at point 76 is mounted in suitable bearings a shaft 77 which supports the forward augers 78 and 79 for rotation (Fig. 2).

The augers 78—79 lie at the lower front entrance to distribution box 62 within the snow scoop 70. Above the augers a plate 80 pivoted at 81 depends across the opening above the auger. The function of this plate 80 will be described later. The snow scoop 70 with sides 72 and 74 makes a channel cut as it feeds into the snow.

The snow auger or screw 78—79 consists of two blades 78 and 79 each of which feed to the center of the machine as viewed in Figure 2. 75

The auger is intended to rotate at about 650 R. P. M. and is preferably about 10" in diameter with a 4" pitch. The auger blades are ribbon in nature rather than solid. This simplifies construction but more important serves much more effectively to break up and lighten snow as it enters the machine. The ribbon augers are supported from the axle by spokes 85 and the construction is such that due to the rotation the augers function as solid blades without the danger of clogging and fouling that might result with solid blades. It will be noted that the inner ends 78A and 79A of augers 78—79 are displaced 180°. This avoids a coinciding V formation which might cause a jamming on large ice blocks. Each end is supported by a spoke 85.

The auger is driven by a pulley 87 and a belt 88. Pulley 87 is mounted on unidirectional shaft 90 journaled at one end on arm 91 leading from fan housing 60 and at the other end in a transmission housing 94. A chain drive may be used but whatever drive is used, a suitable safety guard and snow fender should be provided.

In Figure 7 the transmission housing 94 is shown in section. Drive shaft 95 from engine 28 turns gear 96 which drives spiral gear 97 on shaft 98. Also mounted on shaft 90 are drive pulleys 98 and 99 (Fig. 4) which will be described later in connection with forward traction power.

In housing 94 is a fan shaft 100 which projects into fan housing 60 in the form of a hub 101. Splined on shaft 100 is a double gear 102 which in the position shown engages gear 103 on drive shaft 95. Shaft 95 also carries a gear 105 which drives reverse gear 107. When splined gear 102 is shifted to the left the teeth on a gear portion 108 will engage reverse gear 107 to cause reversal of rotation of shaft 100 and reversal of fan direction. A control yoke 106 on gear 102 is shiftable by a control rod 109 which may be remotely controlled by the operator through a lever 109A and suitable linkage. The direction of auger rotation remains unchanged when fan direction is reversed.

In fan housing 60 mounted on hub 101 is a fan 110 which consists of a circular back plate 112 and radial blades 114. It will be noted that the diameter of the fan is much greater than the space between cover 69 and bottom plate 70 of entrance box 62. There is thus formed a vortex entrance for the fan which avoids back-pressure formation and turbulence. The fan is of rigid construction since the blades 114, which can be about 1½" wide, may be fastened directly to the back plate. The back plate serves to baffle snow from the rear wall of the fan housing and thus prevents build up of snow behind the fan and consequent fan friction.

Drive shaft 95 in transmission housing 94 is connected by suitable universal joints 118 to a power shaft 120 out of a clutch 122 on engine 28. Clutch 122 is engaged and disengaged by an arm 124 actuated by suitable control shaft 125 and lever 126, Fig. 3A. The shaft 125 is formed at the lever end to provide an over center action so that the clutch is locked in disengaged position until lever 126 is moved upward and forward. Engine 28 is preferably an internal combustion engine of relatively light weight which is operated to drive the fan at approximately 1000 R. P. M. The engine preferably should have a rating of 10 horsepower to drive a fan of 24 to 30 inches' diameter.

The engine 28 also furnishes traction power.

A drive transmission illustrated in section in Figure 6 is found in housing 130 supported mainly by the axle 22 and fastened to the side of the main frame by a bracket 132. A gear 134 splined to axle 22 receives empowering force from a shaft 136 in housing 130 from gears 137, 138 and 139. Mounted on shaft 136 are pulleys 148 and 149 in line with pulleys 88 and 99 on shaft 90 (Fig. 4). Belts 150 and 151 connect these respective pulleys. Pulley 148 is substantially smaller than pulley 149 to provide a different speed ratio. Belts 150 and 151 are loosely fitted on the paralleled pulleys and power can be transmitted from shaft 90 to shaft 136 only when one of the belts is tightened.

A forward speed control is provided by two pivoted arms 155 and 156 mounted respectively on an extension of shaft 136 and on an extension 157 of housing 130. As shown in Figure 8, arm 155 is extended upwardly to a lever 158. On the ends of arms 155 and 156 are idle pulleys 163 and 164. Fastened to extension 158 is a pull tube 168 consisting of a pipe slotted at 169. A rod 170 slides in pipe 168 and a cross pin 171 in rod 170 may slide in slot 169, (Fig. 10). Rod 170 connects to a triangle plate 172 fastened, through a shaft 174, to a control lever 175 pivoted on cross bar 56. The triangle plate 172 is suitably pivoted at 173. When lever 175 is pulled back it will shift pull bar 168 rearward and move lever 158 rearward. This movement lifts arm 155 and idle pulley 163 against belt 150 tightening the belt and causing rotation of smaller pulley 148 and forward movement of the tractor at the higher speed.

Fastened to lever 156 is a push bar 179 to which is fastened at the rear end a tube 180. Slidable in tube 180 is a bar 181 leading back to triangle 172. When lever 175 and shaft 174 are moved forward, bar 181 moves against bar 179 to push arm 156 forward. Idle pulley 164 engages and tightens belt 151 leading to the larger pulley 149 and the tractor moves forward at the slower speed.

When lever 175 is moved forwardly, the pin 171 slides in slot 169 to relieve movement of tube 168. When lever 175 is pulled back slip joint 180 relieves movement of bar 179.

The traction wheels 21 are designed for operation in snow and on ice alike and with equal effectiveness. As shown in Figure 9, the center portions 20 of the wheels may be formed as relatively thin discs while the traction rims 21 should be radially about 10% of the diameter. For example, with a 20' wheel, a rim of two inches will suffice. The rim is zig-zag in configuration and the width of the V in each case is such that a relatively large opening is left at the bight in each case. The rims are cut so that the edges as finally formed are on the true periphery of the wheel. With this construction snow cannot pack into the cleats. It extrudes through the cleats when there is any tendency to pack. When the wheels are running on ice the relatively thin V-cleats (1/4 of an inch is suitable) will, by the operation of the pressure principle, melt or cut into the ice and provide adequate traction.

The wheels are connected to the axle 22 by a ratchet pawl drive shown in Figure 12 and of well known construction. This permits ease of turning as the tractor is maneuvered.

The frame of the tractor has been described as made up of inverted U-bars 25 and 26 and the U-shaped bottom 30 and sides 23 and 24. The remainder of the sides is formed by trapezoidal plates 190 and 192 which are bolted to the frame.

On top of the entire structure a cover plate 195 is fastened by loops 196, hooks 197 and springs 198 (Fig. 15). The back of the housing is suitably closed by a back pawl 199.

- 5 In the operation of the snow plow, the auger is first set for depth by the adjustment of the caster wheel 40 as described. The lever 175 may then be moved forward or back depending on whether slow or fast forward traction is desired.
- 10 The snow scoop 70 cuts a square channel in the snow as it progresses. As the auger moves into the snow it will toss it toward the center of the machine and meanwhile the fan 110 is creating a vacuum within box 62. The snow will be pulled through the auger into box 62 where it will be caught up by the air moving through the auger opening and drawn to the fan. The fan forcefully dispels the snow out of the spout 65.
- 15 At all times in this operation the object is to break up and lighten the snow rather than to impact it. The restricted vortex inlet to the fan insures positive air movement at all times.
- 20 When deep snow is encountered of levels above the auger height, the suction in the distribution box 62 will be materially increased since air inlet through the auger will be decreased. Under these circumstances the pivoted plate or vane 80 will be sucked inwardly to furnish mixing air to the fan, and snow that is above the auger will be sucked in above the auger to the fan vortex. The plate 80 has sufficient weight that it will maintain a predetermined suction in the distribution box during all normal operation.
- 25 The entire mechanism housing made up of bottom wall 30, side walls 23 and 24, 190 and 192, the rear wall of fan housing 60 and rear wall 199, is closed at the top by cover plate 195. I propose to discharge exhaust from engine 28 at muffler 200 having outlet 201 into this closed housing to insure that all parts are kept heated and dry and to insure slight pressure within the housing. This will keep out finely powdered snow and prevent fouling of the engine. All shaft openings in the housing walls are preferably sealed by suitable packing.
- 30 The fan direction may be reversed, while the engine is running, by clutch disengagement and actuation of reverse lever 109A. The discharge spout 64 can be easily shifted to the other side by removal of wing bolts 66.
- 35 What I claim is:
- 40 A snow clearing machine for transferring snow particles in suspension from a defined ground area to an indeterminate area which comprises a frame and an automotive prime mover supported on said frame, traction wheels supporting said frame to be driven by said prime mover, a forward overhanging portion on said frame balanced by said prime mover, a high-speed ribbon-type auger mounted at a clearing level on said overhanging portion to be driven by said prime mover, means on said frame forming a vacuum chamber behind said auger having an opening
- 45 just rearward of said auger coextensive in length therewith, a high-speed vacuum-creating and centrifugal snow-dispelling fan mounted on said frame at the rear of said vacuum chamber to be driven by said prime mover to receive snow in
- 50 suspension from said chamber, said fan comprising a circular back plate and radial plates normal thereto mounted on said back plate, means surrounding said fan including an outlet passage directed away from the path of said
